UNITED STATES PATENT OFFICE.

OSCAR H. BAKER, OF FARMINGTON, MINNESOTA.

BED-BOTTOM.

SPECIFICATION forming part of Letters Patent No. 361,665, dated April 26, 1887.
Application filed November 12, 1886. Serial No. 218,988. (No model.)

To all whom it may concern:

Be it known that I, OSCAR H. BAKER, a citizen of the United States, residing at Farmington, Dakota county, Minnesota, have invented a new and useful Improvement in Bed-Bottoms, of which the following is a specification.

My invention relates more particularly to that class of bed-bottoms wherein independent spiral springs are used and are supported on slats. It has for its object to hold all the slats firmly on the same level and to provide a knockdown bed-bottom. I accomplish these results by means simple, economical, and efficient, as is more fully hereinafter described and claimed.

In the accompanying drawings like letters refer to like parts throughout.

Figure 1 is a plan view of part of my bed-bottom. Fig. 2 is a sectional elevation on the line X X' of Fig. 1; and Fig. 3 is a longitudinal section on the line y y', Fig. 1.

A is the side rail of an ordinary bedstead. B are wooden slats of the common form. C are independent spiral springs supported on the slats.

D is a longitudinal girder or cross-tie, which rests on top of the slats, one on each side, near the ends of the slats and just inside the bed-rail. The girders D are provided with hooks d, placed at suitable distances, for engaging eyelets in the canvas cover F.

E is a wire staple having a right-angled upper portion, for embracing the girder D, and a lower extension for embracing the slats B. The staple E is placed with its upper portion over the girder and its lower portion embracing the end of the slat. In putting the parts together the staple is hung by its upper portion to the girder and its lower portion is slipped over the end of the slat. The slats are all attached at their opposite ends to the girders in this way. The slats and girders are thus all detachably bound firmly together. The bottom is kept perfectly level as a whole, and each slat is kept true in its proper position.

F is a canvas cover placed over the top of the springs. At its ends it is provided with pockets formed by a hem and cross-stitches in the material, of a size suitable to admit the top spiral of one of the springs C, as seen in Fig. 1 by dotted lines. On its sides it is pro-

vided with eyelets or other suitable means for engaging the hooks d on the girders. It is placed with its end pockets embracing the springs on the foot and head slats, and is attached by the hooks and eyes to the girders at the side.

By preference, I make the girder D in two pieces, as shown in Fig. 1, jointing the two parts over the center slat, as at g. This is only for convenience of packing. Otherwise it may as well be a single piece extending from the front to the rear slat. The springs may be of any suitable kind and size. Springs of different size or tension may be used in different parts of the bed, according to the probable distribution of the weight of the occupants. Its adaptation to this purpose is one of the advantages of my bed-bottom. Another feature is that there can be no slipping or tilting of the slats. The springs are all held true in their position, and all parts of the bed are firm and stable. As the parts are all detachably held together, it may readily be taken apart and packed in small compass for shipment or storage. In other words, it is a convenient knockdown bed-bottom.

I am aware of the patent to J. Eckart, No. 176,846, of date May 2, 1876, spring bed-bottoms, and I make no claim to the construction therein shown.

What I claim, and desire to secure by Letters Patent of the United States, is as follows:

1. In a bed-bottom, the canvas top F, provided with pockets at its ends for embracing the springs of the end slats, and provided with eyelets on its sides, in combination with the binding-girders D, provided with hooks d, substantially as described, whereby a detachable spring bed-bottom top is obtained.

2. In combination, slats B, binding-girders D, provided with hooks d, staples E, as described, independent springs C, canvas cover F, provided with pockets for springs at its ends, and eyelets on its sides, whereby a knockdown spring bed-bottom is formed, which is firm and stable when the parts are in position, and which can be packed in small compass when taken apart.

OSCAR H. BAKER.

In presence of—

ROSWELL JUDSON,
J. PARKER.
